UNITED STATES PATENT OFFICE.

JOSEPH LOUIS KIEFFER, OF MONTREAL, CANADA.

TAKE-UP MECHANISM FOR SEWING-MACHINES.

SPECIFICATION forming part of Letters Patent No. 696,871, dated April 1, 1902.

Original application filed August 24, 1901, Serial No. 73,201. Divided and this application filed November 14, 1901. Serial No. 82,287. (No model.)

To all whom it may concern:

Be it known that I, JOSEPH LOUIS KIEFFER, a subject of His Majesty the King of Great Britain, residing in the city and district of 5 Montreal, Province of Quebec, Canada, have invented certain new and useful Improvements in Take-Up Mechanism for Sewing-Machines; and I do hereby declare that the following is a full, clear, and exact description 10 of the invention, such as will enable others skilled in the art to which it appertains to make and use the same.

My invention relates to a take-up mechanism for sewing-machines of the class used in 15 sewing boots and shoes by a single waxed-thread chain-stitch, and it is a division of a prior application for shoe-sewing machines filed by me in the United States Patent Office on the 24th day of August, 1901, Serial No. 20 73,201.

The machines on which this invention is designed as an improvement employ a stitch-forming mechanism embracing a curved hooked needle and a gyratory looper adapted 25 to lay a single waxed thread around the looper and to form a chain of stitch-loops which are drawn taut; a slideable presser-foot which during the stitch-forming operation is held firmly in a locked position and is also adapt- 30 ed to yield backwardly a limited distance; a channel-guide and a reciprocator curved awl, which are adapted to have a crosswise or lateral movement given thereto for the purpose of feeding the work the distance of one 35 stitch; a yieldable gage against which the work may rest, and a normally active tension device situated adjacent to the wax-melting pot and having its parts arranged to exert a comparatively strong tension on the thread, 40 said tension device being releasable only at the period when it is desired to remove the work from the machine. With the stitch-forming mechanism of prior machines of the class described is associated a thread-take-up 45 mechanism which becomes operative to draw the slack thread and to tighten a freshly-laid stitch-loop around a stitch-loop previously formed, so as to interlock the stitches.

The improved thread-take-up mechanism 50 of the present invention is situated quite remote from the curved needle and preferably

at a point adjacent to the normally active thread-tension device. Said take-up mechanism embraces two ratchets, around one of which the waxed thread is adapted to be 55 wrapped or coiled, and both of said ratchets are mounted on a common arbor side by side and are made fast one with the other, one ratchet having its teeth arranged reversely to the other. With one of said ratchets normally engages a pawl that prevents under all circumstances the two ratchets from turning in a backward direction, and with the other ratchet is adapted to engage an automatic pawl which at proper intervals prevents either 60 ratchet from turning, such locking of the ratchets by the automatic pawl taking place at that period when the freshly-laid stitch-loop is cast off from the curved needle and when the waxed thread is about to be drawn tightly 65 around the previously-formed stitch-loop. The automatic pawl is impelled in one direction by a spring, and it is operatively connected with a rocker, the latter having an arm provided with a curved track-surface that is 70 offset at its outer extremity. On this track-surface is adapted to ride a roller-shoe, which is mounted on a bell-crank lever that is furnished at its free end with an antifriction-roller arranged to ride in a cam-groove on one 75 of the series of machine-cams which are carried by the cam-shaft. Said cam is arranged and timed to actuate the rocker in a peculiar manner—that is to say, the automatic pawl is restrained from engagement with the 80 ratchets during the period that the curved needle is forced through the stock and is retracted partially therefrom; but at the time when the slack thread should be taken up the automatic pawl is allowed to engage with the 85 ratchets, so as to lock both of them against rotation. At this time the thread-engaging fork becomes active to take up the slack thread from the curved needle, said fork being mounted in and carried by the bell-crank lever, and it is capable of movement in a path 90 tangentially to the circumference of the ratchet, so as to move across the path of the waxed thread as it passes through the ratchet around which it is wrapped to and through 95 the thread passage or tube in the frame of the machine.

The invention further consists in the novel construction and arrangement of parts comprising the improved take-up mechanism, as will be hereinafter more fully described and 5 claimed.

In the drawings hereto annexed, forming a part of this specification, Figure 1 is an elevation looking at one side of the machine. Fig. 2 is another elevation looking at the opposite side of the machine. Fig. 3 is an enlarged vertical section through a portion of the rear of the machine. Fig. 4 is a transverse vertical section in the plane of the dotted line 4 4 on Fig. 3 looking in the direction of the arrow. Figs. 5 and 6 are detail sectional elevations in the planes of the dotted lines 5 5 and 6 6, respectively, on Fig. 4, each looking in the direction of the arrow. Fig. 7 is a detail perspective view of the bell-crank lever which is actuated by one of the machine-cams and which occupies an operative relation to certain parts comprising the improved thread-take-up mechanism.

The same numerals of reference denote like parts in each of the several figures of the drawings.

5 designates the cam-shaft, which is journaled in appropriate bearings of the machine-frame 6, and said shaft is equipped with a plurality of cams for actuating the several working parts of the machine; but as the present invention does not deal with the machine generally I have not considered it necessary to explain all the cams and the parts 35 which they operate. At the front of the machine is the looper 8, which is carried by the looper bar or lever 9. On one side of the looper is arranged the awl-bar 10, adapted to carry the curved awl 11. The channel-guide 40 12 lies adjacent to the curved needle 13, the latter being of the general type having the hook. A work-gage 15 lies below the path of the needle, and it is yieldably supported on the main frame by a slidable bar 16, which is normally kept in position by gearing from the spring-drum 17. The presser-foot 18 is arranged above the work-gage and in a position to have operative relation to the curved 45 needle 13, said presser-foot being attached to 50 a bar 19, which is slidably fitted on the machine-frame. Suitable means are provided for locking this presser-foot bar in its advanced position during the stitch-forming operation, said means generally consisting of 55 the toothed plate 20 and a locking-dog 21, adapted for engagement with said plate. All these parts are ordinary in the art, and as their construction and mode of operation are well understood I will not further describe 60 the same in this specification.

The curved needle 13 is arranged to play in a needle-guide 22, which has operative connection with a yieldable spindle 23, that is equipped with an arm 24, to the free end of 65 which is attached a spring 25, and in the path of this arm 24 is disposed an adjustable stop-plate 26, the whole forming an improved

needle-guide mechanism which constitutes the subject-matter of my application for Letters Patent, Serial No. 73,201, of which the present application is a division.

27 designates the wax-melting pot, (see Fig. 3,) the same being arranged at the rear side of the machine and adapted to be heated in the usual way for the purpose of keeping the 75 wax in a melted condition.

A chambered bracket 28 furnishes the support for the operating devices of the thread-take-up mechanism, as well as the support for the tension mechanism and certain other parts 80 which coöperate with said mechanisms. This bracket is secured to the rear part of the machine-frame in any suitable way, and it is provided with a chamber 29, into which projects the gas-burner 30, the heat from which maintains the bracket in a hot condition when the machine is in operation, as is required in waxed-thread sewing-machines. The rear part of the bracket supports a spindle 31, on which is loosely mounted a tension-wheel 32, 85 the latter having a peripheral groove 33, which is adapted to have the waxed thread coiled or wrapped thereon, as shown by Fig. 3. Said tension-wheel forms one part of the normally active thread-tension mechanism, the latter 95 including a friction-disk, which is loosely mounted on a suitable spindle and is normally pressed by a coiled spring into tight frictional engagement with the tension-wheel, said spring being held in place by a suitable 100 hand-wheel. The normally active tension mechanism is well known to those skilled in the art and is fully disclosed by my concurrent application, Serial No. 73,201.

The machine-frame is provided with a 105 thread passage or tube 34, (see Fig. 3,) the same extending from the rear part of the machine to the front part thereof in order to properly guide the thread to the looper 8, and in the rear end of said thread passage or tube 110 is arranged a guide-roller 35, beneath which the waxed thread is adapted to pass, as shown by Fig. 3. The tension-wheel 32 overhangs the mouth of the melting-pot 27, so that the thread will pass in a straight direction from 115 the pot to the grooved edge of the tension-wheel, around which said thread is wrapped one or more times and from which the thread passes to the take-up mechanism of my invention and to certain other devices which will 120 be hereinafter described.

The chambered bracket 28 is provided with an upstanding post 36, in the upper part of which is secured a horizontal arbor 37, that is held in place by a clamping-screw 38, as 125 shown more clearly by Fig. 4. Loosely mounted on this arbor are the ratchet-wheels 39 40, forming the compound ratchet of the thread-take-up mechanism. (See Figs. 4, 5, and 6.) The ratchet-wheels are arranged side by side 130 in close lateral relation and secured firmly together by the screws 41, which pass therethrough. The connected ratchet-wheels are held against displacement on the arbor by the

post 36 and by a nut 42, which is screwed on the inner end of said arbor, so that the ratchet-wheels will be free to rotate idly on the arbor. The ratchet-wheel 39 is provided with a continuous series of teeth which face in one direction, while the other ratchet 40 is provided with a like series of teeth that face in an opposite direction. The last-mentioned ratchet 40 is also provided with a peripheral groove 43, which is adapted to receive the thread, that may be coiled any desired number of times in said groove. With the teeth of the ratchet-wheel 40 normally engages a check-pawl 44, that is pivoted at 45 on the post 36 and is held in its operative position by a leaf-spring 46, that is also secured to the post, (see Fig. 6,) said check-pawl serving to prevent the compound ratchet from rotating in a backward direction.

47 designates the automatic pawl, which is of the curved form shown more clearly by Figs. 3 and 5, and this pawl is pivoted at a point intermediate of its length by a screw 48, which is secured to the post 36, the beak of said automatic pawl being adapted to engage with the teeth of the ratchet 39. A coiled spring 49 is attached to the post 36 and to the short arm of said automatic pawl 47. Said spring exerts its tension on the pawl in a manner to hold the latter in engagement with the ratchet 39 at certain periods in the operation of the take-up mechanism.

50 designates a rocker, the same consisting of two arms arranged at an angle to each other and one of said arms having operative connection with the heel of the automatic pawl 47. (See Figs. 3 and 5.) One arm of this rocker is fulcrumed, as at 51, on the outstanding lug 52 of the post 36, and this arm of the rocker is provided with a rounded head 53, that is fitted in a rounded recess 54 in the heel of the automatic pawl 47, thus loosely and operatively connecting the rocker to the automatic pawl. The other arm of the rocker 50 extends outwardly from the lug 52 on the post, and this arm of said rocker is formed with a curved track-surface 55, which is offset or curved upwardly, as at 56 in Fig. 3. By connecting the rocker operatively with the pawl the spring 49, which is connected to said pawl, is made to serve as the means for holding the arm, which is provided with the track and offset surfaces, in the path of a roller-shoe 57, the latter being loosely supported by a screw 58 on an angular lever 59, as shown more clearly by Fig. 7. A horizontal spindle or arbor 60 passes through and is supported by the machine-frame 6, said arbor or spindle lying in a plane below the main shaft 5. The angular lever 59 is provided with a hollow boss or hub 61, the latter being loosely fitted on one end of the arbor or spindle 60 and held from displacement thereon by a nut 62^a. (See Fig. 1.) The upper inwardly-extending end of this angular lever 59 is provided with a trundle-roller 62, that is fitted loosely in an irregular cam-groove 63, which

is formed in one of the cams 64, secured on the main shaft 5, said cam-groove having the offset or high part 64^a. (See Fig. 1.) The angular lever 59 is adapted to remain in a stationary position during the greater part of the revolution of the take-up-mechanism cam 64, and the roller-shoe 57 at the free end of said lever 59 is thus adapted to occupy a position on the offset portion 56 of the cam-track, which is provided on one arm of the rocker 50, as best shown by Fig. 3, thereby holding the automatic pawl free from engagement with the teeth of the member 39 of the compound ratchet. When the trundle-roller 62 is acted on by the high part 64^a of the take-up-mechanism cam 64, the angular lever 59 is rocked on the axis afforded by the spindle 60, and the roller-shoe 57 is made to traverse the track-surface 55 of the rocker 50, thereby withdrawing said roller-shoe 57 from the offset part 56 of the rocker and making the parts assume the position shown by Fig. 3, whereby the rocker is released from the restraint of the lever 59 and the shoe 58 and the spring 49 becomes active to move the automatic pawl into engagement with the compound ratchet, thus locking said ratchet against rotation on the axis afforded by the arbor 37 and preventing a continuous movement of the thread around said compound ratchet. The angular lever 59 is furthermore provided at its free end with an inwardly-extending footpiece 65, to which is attached the screw 58, that loosely connects the roller-shoe 57 to the angular lever. This footpiece 65 lies alongside of the inner edge of that arm of the rocker 50 which is formed with a track-surface, and said footpiece is provided with a crotch 66, through which the thread is adapted to pass before it enters the thread tube or passage 34. (See Fig. 3.) In the embodiment of the invention shown by Fig. 7 the footpiece is formed with a ledge or shoulder 67, having an aperture adapted to receive the stem 68 of the thread-fork 69, said stem being clamped adjustably to the footpiece by the set-screw 70. The thread-fork is equipped with a sheave 71, that lies in advance of the crotch 66, and over this sheave is adapted to pass the thread after it leaves the compound ratchet. From this description it will be understood that the thread-fork is mounted on the angular lever 59, so as to be movable therewith in an up-and-down direction and also in a back-and-forth direction between the compound ratchet and the roller 35 in the thread-tube. The roller 71 of the thread-fork lies above the lower edge of the compound ratchet, and said roller and the thread-fork occupy a position between the compound ratchet and the roller 35, whereby the thread-fork and its roller 71 are adapted to move across the path of the thread as it travels from the grooved member 40 of the compound ratchet to the roller 35. This is an important feature of the thread-take-up mechanism, because the upward and rear-

ward movement of the fork 69 and the roller 71 causes a pull to be exerted on that length of the thread which is between the roller 35 and the needle, and this pull on the thread 5 by the fork 69, which travels with the angular lever 59, takes place at the period when the automatic pawl 47 engages with the compound ratchet, so as to lock the latter during such upward and rearward movement of the 10 thread-fork, whereby the slack thread is automatically taken up and drawn backwardly from the needle at the period when the loop is cast off from said needle, said thread-take-up mechanism thus becoming effective at the 15 period when the freshly-laid loop shall have been passed through the previous loop, and thus serves to draw the previous loop to a taut condition and to thereby secure the desired interlocking of the thread-loops. Previous 20 to the next advancement of the curved needle the lever 59 moves so as to advance the roller 57 from the track-surface 55 back to the offset 56 thereof, thereby releasing the pawl 47 from engagement with the compound ratchet, lowering the thread-fork 69 to normal position, and allowing the ratchet to turn in one direction, so as to advance the proper 25 length of thread.

The needle-actuating lever 72 has a rearwardly-extending arm 73, provided with a depending fork 74. The fork is adjustably clamped to the arm 73 and is formed with a stud or roller 75. These parts constitute certain elements of the pull-off mechanism, and other elements of this pull-off mechanism are the lever 76, having the stud or roller 77 and connected by a link 78 with the rear end of the presser-foot bar 19. This pull-off mechanism forms the subject-matter of a separate 35 application, which is filed by me of even date herewith, Serial No. 82,288.

The tension mechanism herein illustrated forms the subject of another copending application filed by me of even date herewith, 40 Serial No. 82,289, to which reference may be had for a description of this mechanism.

Having thus described my invention, what I claim as new is—

1. In a sewing-machine of the class described, a thread-loop-take-up mechanism comprising a revoluble member having a face adapted for engagement by the thread, a le-

ver, a thread-pulling fork carried by the lever and arranged to be moved thereby across the path of the thread leaving said revoluble member on its way to the stitch mechanism, and means caused to be operated by the motion of said lever to lock the revoluble member against rotation during such traversing movement of the thread-pulling fork, substantially as described. 55 60 65

2. In a sewing-machine of the class described, a thread-loop-take-up mechanism comprising a compound-ratchet mechanism having means for preventing rotation thereof in one direction and also provided with a thread-engaging face, an automatic pawl adapted to lock said ratchet against rotation in an opposite direction, a rocker engaging with said automatic pawl, a lever riding upon the rocker, and means for taking up the slack thread at the same time that the ratchet is locked by the automatic pawl, substantially as described. 70 75

3. In a sewing-machine of the class described, a thread-loop-take-up mechanism comprising a compound ratchet, a check-pawl engaging with one ratchet member, an automatic pawl adapted to engage with the other ratchet member, a rocker having an offset on the track-surface thereof and operatively connected with the automatic pawl, a lever arranged to ride on the track-surface of the rocker and adapted to normally rest on the offset thereof, and means for pulling up the slack thread from the needle on the locking engagement of the automatic pawl with said ratchet, substantially as described. 80 85 90

4. In a sewing-machine of the class described, a thread-loop-take-up mechanism comprising a compound ratchet, a check-pawl, an automatic pawl, a rocker connected with the automatic pawl, a cam-actuated lever provided with a footpiece and with a shoe which rides on the rocker, and a thread-pulling fork 95 extending from the footpiece and movable with the lever, substantially as described.

In witness whereof I have hereunto set my hand in the presence of two witnesses.

JOSEPH LOUIS KIEFFER.
